WITNESSES:

UNITED STATES PATENT OFFICE.

CHARLES W. VINCENT, OF ASHLEY, PENNSYLVANIA.

FUNNEL.

1,396,606.

Specification of Letters Patent.

Patented Nov. 8, 1921.

Application filed February 14, 1921. Serial No. 444,737.

To all whom it may concern:

Be it known that I, CHARLES W. VINCENT, a citizen of the United States, residing at Ashley, in the county of Luzerne and State 5 of Pennsylvania, have invented new and useful Improvements in Funnels, of which the following is a specification.

This invention relates to a novel form of funnel mainly designed for filling radiators 10 of automobiles and the like, the principal object of the invention being to provide a funnel whereby water can be poured into the radiator without spilling the same over the radiator and without wasting any 15 through the overflow pipe of the radiator.

Another object of the invention is to provide a collar on the funnel for engaging the filling spout of the radiator to hold the funnel in upright position and also to make the 20 funnel usable on different sizes of radiators.

This invention also consists in certain other features of construction and in the combination and arrangement of the several parts, to be hereinafter fully described, 25 illustrated in the accompanying drawings and specifically pointed out in the appended claims.

In describing my invention in detail, reference will be had to the accompanying 30 drawings wherein like characters denote like or corresponding parts throughout the several views, and in which:—

Figure 1 is an elevation of the funnel constructed in accordance with my invention.

Fig. 2 is a view of the small end of the funnel.

Fig. 3 is a section on line 3—3 of Fig. 1.

Fig. 4 is a view showing how the funnel is used.

Fig. 5 is a section through the filling spout of the radiator and the cylindrical part of the funnel showing how the channel receives the over-flow pipe.

In these views 1 indicates the main part 45 of the funnel and 2 indicates the spout part which is of cylindrical form with a portion of the wall bent inwardly to provide an exterior channel 3 which extends longitudinally of the spout 2. The upper end of this 50 channel is closed.

A collar 4 is placed around the upper end of the part 2 at its junction with the main part of the body, this collar being of cap shape and having a flange 5 at its bottom. 55 This collar is adapted to engage the upper end of the filling spout 6 of the radiator A,

the channel 3 receiving the upper end of the overflow pipe 7 of the radiator.

It will thus be seen that water or the like can be poured into the radiator without 60 danger of spilling the same and without wasting any through the overflow pipe of the radiator. The collar acts to support the funnel in upright position even though the cylindrical part 2 may be of smaller diameter than the interior of the filling spout of the radiator. Thus the collar permits the device to be used with different sizes of 65 radiators.

If desired I may make the collar detachable from the device and if this is done the collar is provided with an inwardly extending ear 8 for engaging the channel, this ear acting to help hold the collar in position on the part 2. 70

My improved funnel will automatically balance itself in an upright position on the radiator filling spout by the walls of channel 3 fitting around the overflow pipe in the radiator. By my arrangement of parts a 75 person can rest one edge of a pail of water upon the funnel so that he can pour in the water rapidly and with but little effort. The flanged cap will also prevent the water, when the radiator is filled too full, from 80 running over the top of the radiator as the surplus water will pass through the overflow pipe in the radiator. 85

The spout of my funnel is made short enough so as to not project below the filling 90 spout of the radiator. Thus there is nothing to obstruct the passage of water from the funnel into the radiator as is the case where the funnel is provided with a long spout which engages the deflector plate in 95 the radiator.

It is thought from the foregoing description that the advantages and novel features of my invention will be readily apparent.

I desire it to be understood that I may 100 make changes in the construction and in the combination and arrangement of the several parts, provided that such changes fall within the scope of the appended claims.

What I claim is:—

1. A funnel for filling radiators for internal combustion engines comprising a body part and a spout part, said spout part having an exterior channel for receiving the upper end of the overflow pipe of the radiator, 110 a cap removably engaging the spout and adapted to engage the filling spout of the

radiator, said cap having an ear thereon for engaging the channel.

2. A funnel for filling radiators for internal combustion engines comprising a body part and a spout part, said spout part having an exterior channel for receiving the upper end of the overflow pipe of the radi-

ator, a cap on the spout and adapted to engage the filling spout of the radiator, said cap having an ear thereon for engaging the 10 channel.

In testimony whereof I affix my signature.

CHARLES W. VINCENT.
